UNITED STATES PATENT OFFICE.

PHILIP LISTEMAN, OF COLLINSVILLE, ILLINOIS.

ROOFING-TONGS.

SPECIFICATION forming part of Letters Patent No. 438,012, dated October 7, 1890.

Application filed September 23, 1889. Serial No. 324,859. (No model.)

To all whom it may concern:

Be it known that I, PHILIP LISTEMAN, of Collinsville, Madison county, Illinois, have made a new and useful Improvement in Roofing-Tongs, of which the following is a full, clear, and exact description.

The improvement relates to the means whereby the tongs can be applied more securely to the seam, to the means whereby the seam may be more perfectly formed immediately in the vicinity of cross-seams in the metal, and to the means by which the final bending of the metal can be more advantageously formed, and so as not to displace the tongs in so doing, all substantially as is hereinafter set forth and claimed, aided by the annexed drawings, making part of this specification, in which—

Figure 1 is a front elevation of the improved tongs; Fig. 2, a rear elevation thereof; Fig. 3, a plan thereof; Fig. 4, a bottom view thereof; Fig. 5, an end elevation thereof, looking in the direction of the arrow 5, Fig. 1; Fig. 6, an end elevation thereof, looking at the opposite end to that shown in Fig. 5; Fig. 7, a vertical section on the line 7 7, Figs. 1 and 2; Fig. 8, a vertical section on the line 8 8, Figs. 1 and 2, but looking in the opposite direction to that of Fig. 7; Fig. 9, a front elevation of the bending-bar; Fig. 10, a bottom view of the stationary jaw; Fig. 11, a front elevation of the stationary jaw; Figs. 12 to 20, views introduced to illustrate the operation of the machine.

The views are not all upon the same scale. The same letters of reference denote the same parts.

Saving as the tongs A are supplemented or modified by the improvement under consideration, they are of the customary form, and they may be of any ordinary form which admits of the embodiment therein of the improvement.

B represents the stationary jaw, C the movable jaw, and D the bending-bar.

As hitherto made, the front face b of the stationary jaw is flat, in consequence of which the tongs are liable to slip upward upon the flanges e e' of the seam E as the jaws are closed thereupon. I overcome this difficulty by providing said face b with a flange, rib, or projection b', Figs. 5, 11, 12, and 13, and when

the movable jaw is closed to grip the flanges e e' a slight bend is, by reason of the projection b', caused in them, and the tongs thereby prevented from slipping. The projection b', in practice, extends along that part of the jaw B used in forming the initial bending of the metal.

The second feature of the improvement is analogous to that above described. At the opposite end of the tongs—namely, the end shown in Figs. 6 and 18—the jaw-face b is notched at b'', and the movable jaw C is provided with a prong c, which, when the jaws are closed, enters the notch b'' and causes the interposed metal of the seam to thereby be slightly indented at that point, and in consequence of such indentation the tongs at that end thereof can obtain a reliable grip upon the seam.

The third feature of the improvement is understood by referring to Figs. 8, 14, 15, 16, 17, 19, and 20. Extending along that part of the jaw-face b of the stationary jaw used in effecting the final bending of the seam is a groove or recess b''. This recess is at the proper height and of sufficient depth and size to admit the thickness of the folded metal occurring immediately at a cross-seam e'', Figs. 8c 16 and 17, in the metal to be seamed. Hitherto at such a point in the seam, and owing to the jaw-face b being substantially flat, the extra thickness of the metal at a cross-seam prevented the movable jaw from properly closing the seam immediately at the sides, respectively, of the cross-seam, and to complete the work the operator had to go over the seam and close it by other means than the tongs. This difficulty is obviated as described. The extra thickness of the metal is, as the movable jaw closes, received into the recess b'', and the seam in the immediate vicinity of the cross-seam, as well as at other points, is thoroughly closed and the face e'' of the seam, Figs. 15, and 17, made substantially flat.

The remaining feature of the improvement is the provision whereby, in effecting the final bending, the bending-bar can be manipulated so as not only to turn the metal over to advantage, but also so as not to cause that end of the tongs to be drawn upward on the seam, and thus displace the tongs and prevent the seam from being properly formed.

Referring to Figs. 8, 19, and 20, it will be seen that the upper corner b^4 of the stationary jaw is not at the center, or in line with the center, upon which the bending-bar D rotates, but a certain distance in front of such center. The bending-bar is also shaped out at d , so that prior to the turning down of the bending-bar a space d intervenes between the corner b^4 and that outer portion d' of the bending-bar which comes in contact with the metal to be bent. Heretofore when the corner b^4 was made to substantially coincide with the center on which the bending-bar rotated the metal was by the action of the bending-bar turned sharply over the corner b^4 , and in consequence of this arrangement the tongs had a tendency to rise upon the seam. The action of the bending-bar operated to pry the tongs upward, so that the bottom of the tongs no longer laid flat upon the main part of the metal. This difficulty is overcome by the means described. The portion d' of the bending-bar encounters the flange first toward the outer edge thereof and operates to roll the flange from the corner b^4 , and it does not bear upon the entire flange until the bending is

about completed, and at that point of the bending the bending-bar is not pressing downward but rather sidewise against the seam, and thus there is no force acting to materially 30 pry the tongs upward on the seam.

I claim—

In roofing-tongs, the combination of the bending-bar having the recess d and flat operating-face d' , the movable jaw C, having the 35 projection c , and the stationary jaw B, having the projection b' , the notch b^3 , to receive and co-operate with the point of the projection c of the movable jaw, the recess b^3 , to co-operate with the operating-face d' of the 40 bending-bar, and the projection or corner b^4 , a suitable distance in front of the axis of rotation of the bending-bar, all constructed and arranged substantially as and for the purposes specified. 45

Witness my hand this 7th day of September, 1889.

PHILIP LISTEMAN.
